INCORPORATED, OF BRIDGEPORT, CONNECTICUT, A CORPORATION OF CONNECTI-
CUT.

SWITCH MOVEMENT.

Application filed April 9, 1926. Serial No. 100,860.

This invention relates to an operating mechanism for electric switches, and particularly to a so-called lock and release mechanism of the type in which there is a spring to oscillate the movable switch element with an operating means for tensioning the spring and a locking device for holding the oscillating element stationary until the spring has been completely wound and then releasing this element so that the full force of the spring is applied to shift the oscillating element to give a rapid make and break with the switch contacts.

It is an object of the invention to provide an improved construction of this type which may be employed with an operating element mounted for turning movements about an axis normal to the plane of the face plate.

With the foregoing and other objects in view, I have devised the construction illustrated in the accompanying drawing forming a part of this specification, similar reference characters being employed throughout the various figures to indicate corresponding elements. In this drawing,

Fig. 1 is a rear elevation of an electric switch and face plate using my improved operating mechanism.

Fig. 2 is a longitudinal section substantially on line 2—2 of Fig. 1 but showing the switch mechanism in elevation.

Fig. 3 is a front elevation of the face plate and the operating element.

Fig. 4 is a longitudinal section through the switch mechanism removed from its support, the section corresponding to the plane of the vertical center line.

Fig. 5 is a transverse section substantially on line 5—5 of Fig. 4 showing the relative position of the operating spring and cooperating elements when the actuating member is at rest and also showing stops for the actuating member.

Fig. 6 is a detail plan of the spring release mechanism at rest in one of its extreme positions.

Fig. 7 is a similar view showing the release mechanism ready to release.

Fig. 8 shows the release mechanism in the released and tripped position.

Fig. 9 shows the relation between the contact blades, release mechanism and stops, and

Fig. 10 shows the relation between the operating spring, the actuating member, release

mechanism and stops in released and tripped position, the plane of the section being substantially on line 10—10 of Fig. 4.

This is the switch operating mechanism disclosed in the copending application of Harvey Hubbell, for switch receptacle, Serial

No. 78,417, filed December 30, 1925. In the arrangement illustrated the insulating body

11 has a chamber 12 open at the rear and in which the switch mechanism is mounted.

Mounted in recesses in this body and projecting into the chamber are stationary contacts

13 secured in position by means of screws 14, and these screws are connected with plates 15

mounted in recesses in the front side of the body carrying binding post screws 16 for connection to the lead wires of the house wiring system.

Secured to the rear face of the body by suitable means, such as screws 17, is a supporting plate 18, and these screws 17 may be

used to secure the yoke members 19 to the forward side of the body and which are used to

secure the device to the usual wall outlet box, not shown. The face plate 20 is normally

mounted by attaching it to these yoke members by the screws 21. The body has a forward extension 22 extending through an opening in the face plate, and this extension has

an opening in which is an operating member

23 mounted for turning movements, this operating member being provided with a pro-

jection 24 forming a finger piece for manual operation of the member. This member is

preferably constructed of suitable insulating material and has molded in it studs 25 by

means of which a plate 26 is secured to the operating member. This plate is rigidly se-

cured to a shaft 27 so that turning movements

of the member 23 will also turn this shaft, and this shaft has a bearing 28 in the supporting

plate 18.

Mounted on the shaft is a pivoted plate or oscillating element 29 carrying a movable switch contact 30 adapted to engage the sta-

tionary contacts 13 and bridge the same and, of course, this movable contact 30 will be

insulated from its support 29. This oscil-

lating element is provided with laterally ex-

tending ears 31 and 31' upon which the mov-

able switch contact 30 is mounted, and a fur-

ther element 32 is mounted on the shaft and assists in supporting the movable switch

contact, this element engaging the end of

the bushing 33 on the shaft to limit the lat-

eral movement of the members 30 and 32. Mounted on this bushing is a coiled spring 34 having oppositely extending free arms 35 and 36 normally engaging the ears 31 and 31' on the oscillating member, and adapted to swing this member in opposite directions under certain conditions to open and close the switch.

The plate 26 mounted on the rear end of 10 the operating member 23 has a pair of rearwardly extending lugs 37 and 38 also arranged to engage the spring arms 35 and 36 respectively for winding or tensioning the spring as the operating member 23 is given 15 its turning movements. The plate 26 is still further provided with stop lugs 39 and 40 adapted to engage the stops 41 extending forwardly from the rear supporting plate 18 to limit the turning movements of the operating member. 20

The oscillating or swinging member 29 has two substantially diametrically opposite extensions 42 and 43 which have stop shoulders 44 and 45 respectively at their opposite ends 25 arranged to engage the sides of the stops 41 on the rear supporting plate 18 to limit the turning movements of the swinging or oscillating member 29. Mounted between the supporting plate 18 and the oscillating member 30 29 is a locking plate 46 which is adapted for limited reciprocating movement and has a stop lug 47 which is arranged to be engaged by the shoulders 45 on the opposite ends of the extension 43 to hold the oscillating member 35 against movement during the operation of the winding of the spring. The locking plate 46 is mounted for limited reciprocatory movement on the supporting plate 18, it being guided in these movements by means of studs 48 carried by the locking plate and projecting into elongated slots 49 in the plate 18.

The locking plate 46 is provided with an opening therethrough and has a pair of tapered cam lugs 50 and 51 projecting inwardly 45 from the opposite sides thereof. Mounted on the shaft 27 so as to turn therewith, and located within the opening in the locking plate, is a cam plate 52. This cam plate has a pair of oppositely extending projections 53 and 54, and intermediate these two projections is provided with a somewhat larger portion 55 having a curved outer edge 56, and the plate is also provided with a concentric curved edge 57 on the opposite side thereof from the 50 curved edge 56. The curved edges 56 and 57 cooperate with the ends of the cam lugs 50 and 51 respectively to hold the locking plate stationary during the winding operations of the spring, or that is, during the movements 55 of the cam plate intermediate the two releasing positions.

The operation is as follows: Assume the elements are in the positions shown in Figs. 5 and 6, which is one of the normal positions of rest, it being understood, of course, that in

this position the switch may be either "on" or "off" depending upon the relative mounting of the movable and stationary switch contacts. If now the operating member 23 is given a partial revolution or turning movement to the right or clockwise, as viewed in these figures, and as indicated by the arrow in Fig. 6, it will be apparent that the locking plate 46 will be held stationary by engagement of the cam lugs 50 and 51 with the concentric curved surfaces 56 and 57 respectively until the shaft has made nearly a quarter revolution when the wall 58 of the extension 54 will engage the inclined wall of the cam lug 51 and will slide the locking plate 46 downwardly a short distance, the upper cam lug 50 moving into the notch 59. The elements are now substantially in the position shown in Fig. 7 and the locking plate 46 still locks the oscillating or swinging member 29 against movement because of the engagement of the left hand shoulder 45 with the stop lug 47 on the locking plate. During this movement the lug 38 on the plate 26 secured to the operating member 23 engages the arm 36 of the spring and forces it away from the lug 31 on the oscillating member and will wind the spring because the other arm 35 of the spring will be held by the other lug 31' on the oscillating member, it being understood that during this movement the oscillating member is held stationary or locked by means of the locking plate. Also, as the lug 38 is moved the opposite lug 37 carried by the plate 26 will be correspondingly moved in a clockwise direction, as viewed in Fig. 5, away from the spring arm 35 as this arm will engage and be held by the lug 31'. The spring is now wound and a slightly further turning movement of the operating member 23 in the same direction will move the locking plate 46 to the position shown in Fig. 8 and will release the oscillating or swinging member 29 which will immediately be swung by the arm 35 of the spring acting on lug 31' to the position shown in Fig. 10. In this position the shoulder 44 on the right hand side of extension 42 will engage the top side of right hand stop 41 on the rear supporting plate and the left hand shoulder 45 on the extension 43 will engage the lower side of the left hand stop 41, and these shoulders and stops will limit the turning movement of the member 29. If the operating member 23 is now released the spring will swing the members back or counter-clockwise sufficiently to cause the locking plate 46 to be moved up to the locking position, that is, the arm 36, as shown in Fig. 10, acting against the lug 38 will swing the plate 26 counter-clockwise as viewed in this figure, until this arm 36 rests against the lug 31 on the oscillating member. If the member 23 is now turned a quarter revolution in the opposite direction the same operation will take place except that it will be reversed and in the

opposite direction to bring the elements back to the position shown in Figs. 5 and 6.

Having thus set forth the nature of my invention, what I claim is:

5. 1. In a switch mechanism an oscillating element, a locking plate mounted for reciprocating movement, coacting locking means carried by the plate and element, said plate having an opening therein and inwardly extending tapered lugs on opposite sides of said opening, a cam mounted for turning movements and located in said opening, said cam having surfaces coacting with the said lugs to shift the plate and unlock the oscillating element, a spring for oscillating said element, and an operating means connected to the cam and arranged to wind said spring.

2. In a switch mechanism an oscillating element, a locking plate mounted for reciprocating movement, coacting locking means carried by the plate and element, said plate having an opening therein and inwardly extending tapered lugs on opposite sides of said opening, a cam plate mounted for turning movements in said opening and provided with two oppositely disposed lugs and an intermediate lug having surfaces coacting with the lugs on the locking plate to shift said plate to unlock the oscillating element, said cam plate being provided with concentric walls on the intermediate lug and on the opposite side of the plate coacting with the tapered lugs to hold the locking plate in locking position during the movements of the cam intermediate the releasing positions, a spring for shifting the oscillating element, and an operating member connected to the cam plate and provided with means for winding the spring during said intermediate movements.

3. In a switch mechanism an oscillating element, a spring for shifting said element, a locking plate mounted for reciprocating movement, coacting locking means carried by the plate and element, said plate having an opening therein and inwardly extending lugs on opposite sides of said opening, a cam plate mounted to turn in said opening, and an operating means connected to turn said cam plate and arranged to wind the spring, said cam plate being provided with surfaces arranged to coact with said lugs to shift the locking plate and unlock the oscillating element and also provided with other surfaces coacting with said lugs to hold the locking plate in locking position during the winding operation.

4. In a switch mechanism a supporting plate, a shaft having a bearing in the plate and extending at right angles thereto, a locking plate guided for reciprocating movement on the supporting plate and having an opening therethrough having inwardly extending tapered lugs on the opposite sides thereof, a cam plate secured to the shaft and located in said opening, said cam plate being provided

with surfaces cooperating with the said lugs to lock the plate in a given position and to shift said plate at predetermined movements of the cam plate, an oscillating element mounted for turning movements on the shaft, 70 coacting locking means carried by the locking plate and the oscillating element, a spring on the shaft to shift the oscillating element, and an operating means secured to the shaft and connected to the spring for winding the 75 same in certain timed relation with the operation of the locking plate.

5. In a switch mechanism, a shaft mounted for turning movements, an oscillating member mounted to turn relative to the shaft, a spring adapted to turn said member in opposite directions, a cam secured to said shaft, a reciprocable locking plate, means for holding said plate against turning movements, coacting locking means carried by the locking plate and the oscillating member, operating means connected to the shaft to impart turning movements thereto and provided with means for winding the spring during said movements, and cooperating means carried by the cam and the locking plate for holding the locking plate and shifting it in certain timed relation with the winding of the spring.

6. In a switch mechanism, a shaft mounted for turning movements, an oscillating member mounted to turn relative to the shaft, a spring adapted to turn said element in opposite directions, a movable locking plate having an opening provided with inwardly extending tapered lugs on the opposite sides thereof, a cam plate secured to the shaft and mounted in said opening, coacting locking means carried by the locking plate and the oscillating member, operating means connected to the shaft for imparting turning movements thereto, means operated by the operating means for winding the spring during said turning movements, and said cam plate being provided with means cooperating with said tapered lugs to hold the locking plate in locking position and shift the same to unlock the oscillating member in certain timed relation with the winding of the spring.

7. In a switch mechanism a movable element mounted for oscillating movement and provided with spaced shoulders, a stationary member having lugs to engage said shoulders to limit the movements of said element, a movable locking plate having stop shoulders to engage certain of the shoulders on the element to hold it in given positions, said locking plate having an opening with inwardly extending tapered lugs on opposite sides thereof, a cam plate mounted to turn in said opening and having surfaces to coact with the tapered lugs to shift the locking plate adjacent the extremes of movement of the cam plate to unlock the oscillating element and to hold the locking plate stationary intermediate the releasing positions, a spring arranged to

shift the oscillating element after it is released, and an operating member mounted to turn the cam plate and wind the spring.

8. In a switch mechanism, a shaft mounted for turning movements, a member mounted to turn relative to said shaft, a spring adapted to turn said member, a cam secured to said shaft, a movable locking plate, coacting locking means carried by the locking plate and said member, operating means connected to the shaft to impart turning movements there-

to, means connected to the shaft to wind the spring by said turning movements, stop means independent of the locking means carried by the locking plate to arrest the movable member at the end of its movements, and cooperating means carried by the cam and the locking plate for holding the locking plate and shifting it in certain timed relation with the winding of the spring. 15

20 In testimony whereof I affix my signature
CARL M. PETERSEN.
